AUTOMATIC X-RAY EXPOSURE CONTROL UNIT

Victor E. De Lucia, Los Angeles, Calif., assignor to Torr
Laboratories, Inc., Los Angeles, Calif.

Filed Feb. 9, 1970, Ser. No. 21,328

Term of patent 14 years

Int. Cl. D24—02; D14—03
U.S. Cl. D83—1

FIG. 1 is a front perspective view of an automatic X-ray exposure control unit showing my new design;

FIG. 2 is a top plan view thereof;

FIG. 3 is a side elevational view of the unit, the two sides being identical; and

FIG. 4 is a rear view of the unit, the rear side being plain.

I claim:

The ornamental design for an automatic X-ray exposure control unit, substantially as shown.
